United States Patent Office.

THOMAS GRAY, OF UNION ROAD, ENGLAND.

Letters Patent No. 63,036, dated March 19, 1867.

IMPROVEMENT IN THE MANUFACTURE OF BLEACHING POWDER.

The Schedule referred to in these Letters Patent and making part of the same.

TO ALL WHOM IT MAY CONCERN:

Be it known that I, THOMAS GRAY, of Union Road, Wandsworth, in the county of Surrey, England, have invented a new and improved Method of Preparing and Manufacturing Bleaching Powders, Materials and Compounds; and I do hereby declare that the following is a full and exact description of the mode of preparing and manufacturing the same.

It is well known that chloride of lime is the substance or compound usually employed for bleaching fabrics and fibres, and that unless the process be carefully conducted there is risk of injuring or weakening the fabric or fabrics under operation.

It is believed that this arises from the presence of free acid in the bleaching compound, and that this acid not only injures or weakens the fibres but also retards the bleaching operation.

The object of the present invention is to eliminate this acid from the bleaching compound, or, at any rate, to neutralize it, so that even if the acid be present it will be inert.

I have discovered various ways of effecting this object, but the particular process to be employed must depend upon the circumstances of the case to be treated.

The ordinary method of manufacturing bleaching powder consists in impregnating ground lime with chlorine gas; but as this nearly always contains free acid, one of my processes consists in passing the chlorine gas through a solution of caustic soda in water before allowing it to enter the chamber or vessel in which it is brought in contact with the lime.

Sometimes it will be found more convenient to mix the soda-ash, caustic soda, or other alkali, with the ground lime, so that when the chlorine gas is brought to the lime the free acid may combine with the soda ash or caustic alkali, and thus remain inert in the compound.

As a modification of this latter process, the soda ash or other caustic alkali may be intimately mixed in a pulverized state with bleaching powder or chloride of lime made in the ordinary manner.

What I claim as my invention, and desire to secure by Letters Patent, is—

The application, as before stated, for the purposes of bleaching fabrics, or fibres, or other materials, without destroying or injuring them, substantially as described.
